HANDLE FOR MATTRESSES AND THE LIKE
AND METHOD OF MAKING THE SAME

Michael Bechik, St. Paul, Minn.

Application September 14, 1936, Serial No. 100,635

5 Claims. (Cl. 5—345)

This invention relates to a mattress and cushion handle wherein it is desirable to provide a handle formed of a ribbon-like webbing which extends along the boxing longitudinally, and which is adapted to be anchored at its ends with finishing plates.

A primary feature resides in providing a handle for a mattress, cushion and the like, wherein a reinforcing inner flexible ribbon-like leaf spring is adapted to form an anchoring means, spacer, and a flexible reinforcing plate means extending longitudinally of the boxing in line with the web handle on the outside of the boxing.

Further, the flexible reinforcing ribbon-like leaf spring provides a load bearing plate for the ends of the handle so that any strain carried by the handle will be transmitted to the inner wall of the boxing and carried by the load bearing plate-like ends of the flexible reinforcing member.

The invention further includes a unitary assembly of the webbing handle with the end finishing plate eyelets. This unit assembly includes the ribbon-like web handle with holes punched in the end and the end finishing eyelet plates secured through the hole to form a reinforcing eyelet and adapted to cover the end of the web handle providing a finishing end member as well as a reinforcing eyelet which individually and separately attaches and clamps to the ends of the web handle.

It is also a feature of this invention to provide a unitary reinforced and finished end web handle which is adapted to be attached to a boxing by ventilator eyelets to connect the handle to the leaf spring anchoring plate extending in line with the handle along the inner surface of the boxing, the ventilating eyelets serving to attach the unit web handle assembly to the load bearing plate ends of the flexible anchoring member. Thus the ventilator eyelets do not act independently to attach the end finishing plates of the handle assembly and the flexible inner reinforcing means to the boxing. Therefore I provide a very desirable handle of this character because it is much stronger, the webbing of the handle being reinforced separately of the ventilating eyelets to prevent pulling out of the ends of the web handle.

A further feature resides in an end finishing plate having an arcuated inner edge rather than a straight transverse edge which permits the flexing of the handle without undue strain on the edges of the finishing plate.

In the drawing forming part of this specification:

Figure 1 is a perspective detail portion of a portion of a mattress or cushion, showing my handle attached thereto.

Figure 2 is a longitudinal enlarged section of my handle, showing the web handle bowed outwardly and the boxing wall with the inner reinforcing anchoring leaf spring plate bowed inward.

Figure 3 is a longitudinal enlarged section, similar to Figure 2, however, showing the web handle lying flat against the outer surface of the boxing, while the anchoring leaf spring lies flat against the inner wall of the boxing, the anchoring leaf spring acting as a spring force to position the handle in this position when not engaged.

Figure 4 is an enlarged inner view of the unit web handle, showing end plate eyelets attached to the webbing.

Figure 5 is an outer perspective view of one of the end plate eyelets.

Figure 6 is an inner perspective view of the end plate eyelet.

Figure 7 is a perspective view of the ventilating eyelet or grommet.

The drawing illustrates a portion of a mattress or cushion A which is provided with a vertical boxing wall B which extends about the mattress or cushion. The feature of this invention is to provide a handle C which may be easily engaged by the hand to lift the mattress or cushion, and in the construction illustrated, the hand engaging portion 10 of the handle is formed of any suitable webbing to provide a ribbon-like construction. It is important in attaching the handle C that a strong, durable construction be provided which will permit mattresses or cushions, even of the heavier type, to be readily lifted and carried by these handles.

The ribbon-like webbing handle 10 is adapted to be formed into a unit by providing finishing end plate eyelets 11 which are formed with a round end portion 12 and an inner arcuated edge portion 13. The finishing end plate eyelets are formed with a reinforcing rearwardly projecting flange 14 which extends around the end 12 and which is pivotal at its ends where it joins with the arcuated inner edge 13. These end plates 11 are formed with an inwardly extending collar portion 15 to provide an eyelet when the inner edges of the collar 15 are turned over to provide anchoring flange means 16 which extend around a hole formed in the ends of the webbing 10 to reinforce the hole and to securely anchor the ends of the web handle 10 to the end finishing plate 55.

eyelets 11. This handle unit assembly is then ready to be attached to the boxing of the cushion or mattress.

The finishing end plate eyelets are formed 5 with a countersunk annular recess 17 which is adapted to receive the annular flange 18 formed on the ventilating grommet or eyelet 19 about the ventilating screen portion 20. The grommet or eyelet 19 is provided with a cylindrical sleeve 21 which extends through the eyelet 11 and through a hole formed in the end of the flexible leaf spring anchoring plate 22 as illustrated in Figure 3. When the eyelet 19 is in the proper position to secure the handle 10 to the boxing 10 wall, the inner edges of the sleeve 21 are peaned over at 23 against the load bearing plate ends 15 24 of the reinforcing spring 22. The body of the boxing B is of soft felted material and is compressed by the anchoring ventilating eyelet 19 20 to rigidly secure the handle assembly unit to the outer wall of the boxing B.

The web handle 10 extends in line with the flexible leaf reinforcing inner spring 22. The boxing B is flexible so that it will flex inwardly 25 with the reinforcing spring 22, while the web handle 10 flexes outwardly to admit the hand, thus providing a handle which may be easily engaged by virtue of the inwardly flexing anchoring spring 22 and boxing wall B and the outwardly flexing web handle 10. The spring reinforcing anchoring member 22 acts to space the 30 ends of the handle 10 apart and the ends of said spring provide load bearing plates 24 so that the wall B of the mattress or cushion will not be torn, but will be securely held under the flange 14 and the load bearing end plate portions 24. This is extremely important because considerable 35 strain is applied to a handle of this character when lifting a heavy mattress or cushion. It is of equal importance to provide the web handle 10 with reinforcing finishing end plate eyelets 11 which are separately attached to the web handle to form the handle unit and to prevent the tearing out of the webbing around the holes in the ends of the same. The ventilator grommets 19 provide air passageways through the 40 walls of the mattress.

In accordance with the patent statutes I have described the construction of my handle for mattresses, cushions and the like, together with the 45 method of making the same, and while the drawing illustrates one embodiment thereof, the invention should be interpreted within the scope of the following claims:

50 I claim:

55 1. A handle for a mattress and cushion having a flexible wall including a webbing handle member having openings punched near the ends of

the same, finishing plates registering with the ends of said handle member, eyelet means on said plates extending through the openings for securing said finishing plates in overlying relation to the ends of said handle member, a resilient back bar overlying the inner surface of the flexible wall, and grommets extending through said eyelets and the flexible wall securing said handle member overlying the outer surface of said flexible wall to said resilient back bar. 5 10

2. A handle assembly for a flexible wall comprising a flexible handle, finishing plates overlying the ends of said handle, eyelet means extending through said handle and plates securing the same together, a spring bar overlying one surface of said wall, and grommet means extending through said eyelets, said wall, and said spring bar securing said spring bar to said handle on the other surface of said wall. 15

3. A handle assembly for flexible walls comprising a spring bar overlying one surface of said wall, a flexible handle overlying the other surface of said wall, reinforcing means for the ends of said handle, means securing said reinforcing means to said handle, said handle, reinforcing 25 means, wall, and spring bar having spaced registering openings therethrough, and means extending through said openings connecting said bar with said handle stretching said handle taut and compressing said wall to hold said handle from 30 movement with respect to said bar.

4. A handle assembly in combination with a flexible wall comprising a flexible handle having spaced openings therethrough, opening reinforcing means enclosing the edges of said openings, 35 a resilient plate overlying the surface of said flexible wall and having openings therethrough registerable with said openings in said handle, and means extending through the cooperating openings in said bar and handle and extending 40 through said wall intermediate said handle and bar, said resilient plate holding said handle taut and said last named means compressing said wall to prevent relative movement between said handle and bar adjacent said extending means. 45

5. A reinforced handle in combination with a flexible wall comprising a flexible strap overlying said wall, a reinforcing plate overlying each end of said strap, a flanged edge on said plate, an arcuated end of said plate, said flanged edge extending along said arcuated end, registerable openings in said strap and plate, and eyelet means extending through said openings and securing said strap and plate together, reinforcing means on the opposite side of said wall from 50 said strap, and grommets extending through said eyelets, wall, and reinforcing means. 55

MICHAEL BECHIK.
